UNITED STATES PATENT OFFICE.

EDWARD E. KLEINSCHMIDT, OF BROOKLYN, NEW YORK.

KEYBOARD TAPE PERFORATOR.

1,420,931.

Specification of Letters Patent. Patented June 27, 1922.

Application filed July 16, 1919. Serial No. 311,328.

To all whom it may concern:

Be it known that I, EDWARD E. KLEINSCHMIDT, a citizen of the United States, residing in New York, borough of Brooklyn, 5 in the county of Kings and State of New York, have invented certain new and useful Improvements in a Keyboard Tape Perforator, of which the following is a specification.

10 My invention relates to an apparatus which is particularly applicable for perforating tape by means of punches which are actuated in combinations to form corresponding combinations of openings in the tape, 15 so that when the latter is passed through a transmitter, the message which has been perforated in the tape may be sent.

In the embodiment of my invention here shown, the tape is perforated in general in 20 accordance with the Baudot system.

My invention has for one of its objects the provision of a simple, compact and efficient apparatus for performing the perforating operation.

25 Another object of my invention is the provision of an indicating mechanism particularly applicable to a perforating machine, but which is obviously applicable to other uses.

30 My invention will best be understood by reference to the accompanying drawings, in which Fig. 1 is a plan view of the perforating machine embodying my invention; Fig. 2 is a longitudinal section of Fig. 1; 35 Fig. 3 is a vertical section at right angles to Fig. 2; Fig. 4 is a plan view of the punching mechanism and the parts associated therewith, the cover plate for the mechanism being removed; Fig. 5 is a side elevation of 40 the punching mechanism; Fig. 6 is a side elevation, partially in section, at right angles to Fig. 5; Fig. 7 is a detail view showing particularly the manually-operated mechanism for returning the tape through the perforator; Fig. 8 is a side view of the counting mechanism; Fig. 9 is an end view, partially in section, of the counting mechanism; Fig. 10 is a detail view illustrating the adjustable arrangement for the punch controllers; Fig. 11 is a diagram showing the circuit in which is included the punch actuating magnet, and Fig. 12 is a diagram illustrating the lamp circuit.

Referring, now, to the drawings, in which 55 I have shown one embodiment of my invention and in which like reference charac-

ters indicate like parts, 10 is the frame of the machine, which may be provided with resilient bearing-feet 11. The perforator is actuated by key-bars 12, on the ends of which 60 are secured finger keys 13. Operating bars 14, which I shall for convenience term T-bars, are disposed beneath the key-bars and extend transversely thereof. Certain of these key-bars, which are here shown as five 65 in number and indicated by the characters 14^a (see Fig. 2), are used for operating the punch controllers; a sixth bar, 14^b, actuates contacts which control the circuit for the operating magnet for the punches, while the 70 seventh bar, 14^c, actuates the counting mechanism.

The cross pieces of the key-bars are notched on their under sides, as at 15 (see Fig. 2), leaving projections 16 which engage the upper edges of the T-bars, it being understood that the notches and projections are so arranged as to depress the T-bars in various combinations corresponding to the particular key character carried by 80 the key-bar. In order that the T-bars may all be depressed substantially the same amount by the various key-bars, the key-bars 12^a associated with the front bank of keys are pivoted at the rear of the machine 85 on a transverse arm 17, while the key-bars 12^b associated with the middle and rear banks of finger keys are pivoted on a transverse bar 18 in advance of the bar 17, such an arrangement producing a sufficiently uniform depression of the T-bars by the various key-bars. The key-bars are normally held in an elevated position by springs 19 connected to the ends of the key-bars which project beyond the plates 17 and 18, the 90 other ends of the springs being connected to a stationary member, as best shown in Fig. 2.

Each of the T-bars 14 is provided with a downwardly extending stem 20, as best shown in Fig. 3. A lever 21 for actuating a corresponding punch controller is pivoted to each of the T-bars 14^a, each lever being pivoted at an intermediate point at 22 in a bracket or bar 23 secured to the frame, the outer ends of the levers 21 normally being depressed by springs 21^a. A second bar 24, parallel to the bar 21, is pivoted to the lower end of the stem 20 of the T-bar, the other end of the bar 24 being pivoted at 25 to the bar 23, the parts being so arranged as to form a parallelogram, which insures parallel 100 105 110

movement to the T-bar in its downward movement. The free end of each of the levers 21 is pivoted, preferably by means of a pin and slot connection, as shown in Fig. 3, 5 to one end of a bell-crank 26 pivoted at 27 in a bracket 28 secured on a base plate 29, which acts as a support for the punching mechanism and is secured to the frame of the machine. The downward movement of the 10 T-bar thus elevates the free end of the lever 21 and correspondingly the end of the bell-crank to which this lever is connected and throws the vertical arm of the bell crank lever to the left, as viewed in Figs. 3 and 6, 15 to bring the punch controllers into operative position beneath the punches in a manner that will presently be described.

In accordance with my invention, provision is made for adjusting the positions of 20 the punch controllers by providing an adjustable extension 21^a on the ends of the levers 21. The two members 21 and 21^a are pivoted together at 21^b, and are provided with laterally extending arms, the arm for the 25 extension 21^a, which is indicated at 21^c, being provided with an arcuate slot 21^d, in which is received a pin 21^e secured to the lateral arm of the lever 21, which arm is disposed behind the arm 21^c, and is only partially shown in dotted lines in Fig. 10. The 30 two lateral arms are secured together by a clamping nut 21^f. By loosening the nut 21^f, the extension 21^a may be raised or lowered as desired to position the corresponding 35 punch controller.

In accordance with my invention, the 40 punch controllers are mounted in and movable with a head which is directly actuated by the core of the operating solenoid, and the construction by which this result is accomplished constitutes one of the important 45 features of my invention. The punch controllers 30 are made in the form of slide bars, the outer ends of which are pivoted at 31 to the upper ends of the bell-crank levers 26. The inner or free ends of the punch controllers are received in slots 32 formed in a saddle 33 which is mounted on the vertically-movable operating head 34, as best 50 shown in Figs. 5 and 6. Above the controllers 30 are disposed punches 35 corresponding in number (five in the embodiment here shown) to the punch controllers. The punches pass through suitable openings provided in an upper guide plate 36, forming a 55 part of the cover for the controllers, and also through openings in a lower guide plate 37, forming the lower part of a yoke-shaped bracket 38 secured beneath the cover plate. The punches are provided with collars 39, and they are all normally depressed with the 60 collars resting against the lower guide plate 37 by a comb 40, which is pivoted at 41, the comb being forced downwardly by a spring 65 42 (see Figs. 4 and 6), a plate or washer 43

provided with openings closely surrounding the punches being disposed between the comb and the collars. The purpose of this plate or washer is to prevent the comb, which would engage the collars only at two diametrically opposite parts, from wearing away the collars. The lower ends of the punches, which project beneath the plate 37, register with the punch controllers 30. The inner ends of the latter are notched, as at 70 44 (Fig. 6), leaving a reduced section which always engages within the slots 32 in the saddle 33, and act as guides, the reduced section of the controller, however, not being thick enough to engage the lower ends of the 75 punches when the operating head is elevated. When the head is raised, therefore, with the punch controller occupying the position shown in Fig. 6, the controller does not engage the punch. When, however, the controller is moved to the left, as viewed in Fig. 6, the unreduced portion of the end of the punch controller is brought beneath the punch, and when the operating head is raised, in a manner which will be more fully 80 90 hereinafter described, the corresponding punch is raised to perforate the paper. A die plate 45 is disposed above the cover plate 36, and is provided with openings 46 registering with the punches. A slot 47 is provided between the die plate and the cover plate, 95 through which the paper to be perforated passes. One of the punches 35^a (see Fig. 5) which may be smaller than the message perforating punches, is used for punching feed 100 holes in the paper. The punch 35^a is engaged by a stud or pin 48 mounted on the operating head, which actuates the feed punch each time that the operating head is raised. Since the operating head is attached 105 directly to and forms a part of the core 74, and the ends of the punch controllers are disposed between the operating head and the punches, the impact of the core 74 produces a hammer effect on the punches which 110 greatly increases the certainty and effectiveness of the punching operation.

The paper is fed forward each time the operating head is actuated by a pawl 49 which engages a ratchet 50 mounted on a 115 shaft 51 having its bearings in a yoke-shaped bracket 52 (see Figs. 5 and 7) secured on the under side of the cover plate of the punch controllers. A feed wheel 53 is also secured on the shaft 51 and is provided, on its periphery, with pins which engage the feed openings in the tape in a well understood manner. A skeleton presser bar 54 having a loop disposed above the feed wheel is secured on the upper side of the cover plate, 115 as shown in Fig. 1, to maintain the paper in engagement with the feed wheel and at the same time render the tape visible to the operator. The pawl 49 is held in engagement with the ratchet 50 by a spring 55, the pawl 120

- and ratchet mechanism being actuated on the downward movement of the operating head. A spring-pressed jockey roller 56 engages the ratchet 50 to prevent the latter from overstepping. In order to enable the operator to feed the tape backward through the machine and correct any error that may have been made in the perforations, a manually-operated lever 57 is provided which is pivoted at 58, as best shown in Fig. 7. The end of the lever is provided with a finger key 59, the opposite end of the lever being normally depressed by a coil spring 60. The inner end of the lever 57 is provided with a cam member 61 which engages a stud 62 secured on the side of the pawl 49, so that when the key 59 is depressed the cam member 61 is raised and forces the pawl 49 away from engagement with the ratchet 50.
- The lever 57 is also provided with a pawl 63, as best shown in Fig. 4, pivoted at 64 on a lug 65 projecting laterally from the lever 57. The pawl 63 engages one of the teeth on the feed wheel 53 after the pawl 49 has been released from its ratchet and rotates the feed wheel backwards sufficiently to bring the improperly punched openings opposite the punches. The operator may then, by actuating the letter key (designated LTRS in Fig. 1), operate all of the punches and this acts as an erasure. A chute is preferably disposed above the punches to carry away the punchings from the tape. The paper tape 67 (indicated by diverging dotted lines in Fig. 1) which is to be perforated, may conveniently be wound upon a spool 68 mounted in a disc-shaped casing 69, the tape passing through an opening 70 (see Fig. 1) in the side wall of the casing. A collapsible copy holder 69^a is preferably mounted on the top of the disc-shaped receptacle. The receptacle 69 may be mounted on the cover 71 of the machine.
- The punch-operating head 34 is actuated by a solenoid 72 which is energized in response to the actuation of any one of the finger keys of the keyboard. The solenoid is mounted on the base plate 29 and is surrounded by a yoke 73 of magnetic material.
- The solenoid is provided with a core 74 secured in any desired manner to a non-magnetic member (indicated in dotted lines in Fig. 6) and secured to the operating head 34. The circuit of the magnet 72 is controlled by a pair of contacts 75 and 76 (see Figs. 3 and 11) the contact 75 being carried by and movable with the stem 20 of the T-bar 14^b. Any suitable source of energy, such as a battery 77, which may be connected to a terminal block 78, is included in the circuit of the magnet 72. It will, of course, be understood that each of the key-bars is arranged to depress the T-bar 14^b when actuated, the depression of the T-bar closing the contacts 75 and 76.
- I will now describe the construction and operation of the counter, which affords the operator a visible indication of the number of character spaces that have been formed in a given line and a separate indication 70 when a sufficient number of the character keys have been depressed to bring the paper in the typewriter printer, which is actuated in response to the transmitter through which the tape is passed, to the end of the 75 line.
- In the embodiment of my invention here shown, the counter comprises an indicator wheel 80 mounted on a shaft having its bearings in a plate or bracket 81 secured on the 80 frame of the machine. The wheel is provided on its periphery with numbers 82 which are visible through an opening 83 in the cover 71 of the machine (see Fig. 1), the number which is visible indicating the 85 extent to which the wheel has been rotated and correspondingly indicating the aggregate number of character keys that have been depressed and the movement of the paper carriage of the printer. Secured 90 on one side of the wheel 80 is a ratchet 84 which is actuated by a pawl 85 pivoted on an arm 86 which is, in turn, pivoted at 87 on the bracket 81, the pawl being forced towards the ratchet and actuated by a spring 95 88. The outer end of the arm 86 is disposed above the T-bar 14^c which is especially provided for actuating the counter. In operation, the depression of the T-bar 14^c permits the spring 88 to actuate the pawl 85, the 100 T-bar 14^c actuating the arm 86 and the pawl 85 on its return. The T-bar 14^c is actuated by each of the character keys, but is not actuated by such keys as the carriage return (CARR. RET.) and the line feed keys. A 105 retaining pawl 89 is held in engagement with the ratchet 84 by a spring 90, the end of which pawl is formed to engage the end of the pawl 85 and acts as a stop to limit its movement. The key-bar associated with the 110 carriage return key carries a downwardly projecting arm 91 (see Fig. 8) which, when depressed, engages an arm 89^a projecting from the pawl 89, in order to release the pawl from the ratchet 84. The pawl 89 is also 115 provided with an arm 89^b which engages a tail-piece on the pawl 85 when the retaining pawl is released from the ratchet and moves the pawl 85 away from the ratchet. The pawl 89 is further provided with an arm 120 89^c which engages a notch 97 in an arm 98 pivoted at 99 and pressed towards the arm 89^c by a spring 100 when the pawl 89 is released from the ratchet. These parts are provided in order to insure the return of the 125 indicator wheel to its zero position when the same has been released. When the pawls are thus released from the ratchet 84, the latter is returned to its zero position by a spring 92 (shown in dotted lines in Fig. 8). 130

The indicator wheel is stopped in its zero position by a stud 93 secured on the side of the wheel, which engages an arm 94 which is preferably formed as part of an elbow lever, 5 the opposite arm of which is provided with a lateral extension 95 on which is secured a yielding member 96 of felt or other yielding material to absorb the shock on the return of the indicator.

10 In order to afford the operator an additional indication when the counter mechanism has been moved an extent corresponding to the spaces which would carry the carriage of a typewriter to the end of the line, an electric circuit is provided in which is included an indicator, such as an incandescent lamp. The mechanism which closes this circuit comprises a bell-crank 101 pivoted at 101^a in the bracket 81, one arm of the bell-crank being disposed adjacent the indicator and provided with a cam surface 102, arranged to be engaged by the pin or stud 93 on the indicator wheel when the latter has reached the end of its rotation. The upper 25 end of the bell-crank is then moved to the right, as viewed in Fig. 8, and the other arm of the bell-crank carrying an insulating pin or member 103 is depressed. The pin 103 engages a spring-blade 104 carrying a 30 contact 105, which, when depressed, engages a second contact 106 carried by a spring-blade 107. The engagement of these contacts closes a circuit for a lamp 108 which is shown diagrammatically in Fig. 12 and in 35 full in Fig. 2, the lamp preferably being disposed beneath the bank of keys to afford the operator an additional visible signal when the line space has been filled. Any suitable source of electric energy, such as 40 the battery 109 illustrated, is included in the circuit of the lamp. The indicator wheel is provided with a stud 109^a which engages the upper end of the arm 98 when the indicator wheel returns to its zero position, in order 45 to release the arm 89^a of the pawl from the notch 97, and thus insure the return of all parts to normal.

What I claim and desire to secure by Letters Patent of the United States is:—

50 1. In a perforating machine, a plurality of punches for perforating the tape, a single electromagnet and its movable core substantially co-axial with, and arranged for actuating said punches, a reciprocating punch-operating head disposed between said magnet and said punches, a plurality of punch controllers movable into and out of operative registry with said punches, a keyboard selector mechanism constructed and arranged to set said punch controllers in combinations corresponding to the characters on the keyboard, said head being attached directly to and operable by the armature of said magnet.

65 2. In a perforating machine, a plurality

of punches for perforating the tape, a single solenoid and its movable core substantially co-axial with and arranged for actuating said punches, a reciprocating punch-operating head disposed between said solenoid and said punches, a plurality of punch controllers movable into and out of operative registry with said punches, a keyboard selector mechanism constructed and arranged to set said punch controllers in combinations corresponding to the characters on the keyboard, said head being attached directly to and operable by the core of said solenoid, the punch controller being located between said head and the punches. 70

3. In a perforating machine, a plurality of punches for perforating the tape, a solenoid and its core for actuating said punches, a reciprocating punch-operating head disposed between said solenoid and said punches, a plurality of punch controllers carried by said head and movable into and out of operative registry with said punches, a keyboard selector mechanism constructed and arranged to set said punch controllers in combinations corresponding to the character on the keyboard, said head being directly attached to and operable by the core of said solenoid, and said head being provided with a saddle formed with slots within which the punch controllers are received. 80

4. In a perforating machine, a plurality of punches for perforating the tape, a solenoid and its core for actuating said punches, a reciprocating punch-operating head attached directly to said core and disposed between said solenoid and said punches, a plurality of punch controllers carried by said head and movable into and out of operative registry with said punches, a keyboard selector mechanism constructed and arranged to set said punch controllers in combinations corresponding to the characters on the keyboard, said head being provided with a saddle formed with slots, the controllers being formed with reduced sections received within said slots. 100

5. In a perforating machine, a plurality of punches for perforating the tape, means for actuating said punches, punch controllers movable into and out of registry with said punches, a keyboard selector mechanism constructed and arranged to set said punch controllers in combinations corresponding to the characters on the keyboard, said mechanism comprising a lever provided with an extension adjustable with respect to the main lever, whereby the position of the corresponding punch controller may be adjusted. 115

6. In a perforating machine, a plurality of punches for perforating the tape, means for actuating said punches, punch controllers movable into and out of registry with said punches, a keyboard selector mechanism constructed and arranged to set said punch 120

130

- controllers in combinations corresponding to the characters on the keyboard, said mechanism comprising bell-crank, one end of each of which operates a corresponding punch controller and to the other end of which is connected the end of an operating lever, said lever being provided with an extension adjustable with respect to the main lever, whereby the normal position of said punch controller may be adjusted.
7. In combination with a plurality of tape perforating punches provided with collars, means for operating said punches, means for guiding said punches, and means common to said punches and engaging said collars for returning said punches to normal position.
8. In combination with a plurality of tape perforating punches provided with collars, means for operating said punches, means for guiding said punches, means common to said punches and engaging said collars for returning said punches to normal position, and a plate having openings to receive said punches and located between said returning means and said collars.
9. In a machine for use in printing telegraph systems and the like, keyboard mechanism comprising an operating bar actuated only by the character keys, a step-by-step indicator, means operated mechanically by the actuation of said operating bar for actuating said indicator, an electrical indicator, and means for operating said electrical indicator when said step-by-step indicator reaches a predetermined position.
10. In a machine for use in telegraph printing systems and the like, keyboard mechanism containing a plurality of keybars, a common operating bar actuated by each of said keybars, an indicator, and means controlled by said operating bar for operating said indicator.
11. In a machine for use in printing telegraph systems and the like, a keyboard mechanism comprising an operating bar actuated by each of the character keys, a counter-mechanism actuated by said operating bar and comprising a ratchet for operating the counter, an operating pawl for operating said ratchet, and a retaining pawl arranged to be engaged by and act as a stop for said operating pawl.
12. In a machine for use in printing telegraph systems and the like, a keyboard mechanism comprising an operating bar actuated by each of the character keys, a counter-mechanism actuated by said operating bar and comprising a ratchet for operating the counter, an operating pawl for said ratchet, and a retaining pawl for the ratchet constructed and arranged to act as a stop for said operating pawl, and on disengagement from the ratchet to disengage the operating pawl.
13. In a machine for use in printing telegraph systems and the like, a keyboard mechanism comprising an operating bar actuated by each of the character keys, a counter-mechanism actuated by said operating bar and comprising a ratchet for operating the counter, an operating pawl for operating said ratchet, and a retaining pawl formed with an arm arranged to engage the operating pawl and act as a stop therefor and also formed with an arm arranged to disengage the operating pawl from the ratchet when the retaining pawl is disengaged.
14. In a perforating machine, a feed wheel for feeding the tape forwardly, a ratchet movable with said feed wheel, an operating pawl for rotating said ratchet, and means for disengaging said pawl from its ratchet, and simultaneously rotating the feed wheel backwardly.
15. In a perforating machine, a feed wheel for feeding the tape forwardly, a ratchet movable with said feed wheel, an operating pawl for rotating said ratchet, and a manually operated member for disengaging said pawl from its ratchet and simultaneously rotating the feed wheel backwardly.
16. In combination, a tape feed wheel, perforating means for the tape, a single electromagnet having a core armature, a pawl carried by said armature for actuating said feed wheel, and means operable by said armature for actuating said perforating means.
17. In combination, a tape feed wheel, perforating means for the tape, a single electromagnet having a core armature, means carried by said armature for rotating said feed wheel in one direction, and means for releasing said rotating means to rotate said feed wheel in the opposite direction.
18. In combination, a tape feed wheel, perforating means for the tape, a single electromagnet having a core armature, a pawl carried by said armature for rotating said feed wheel in one direction, and means for releasing said pawl to rotate said feed wheel in the opposite direction.
19. In combination, a tape feed wheel, perforating means for the tape, a single electromagnet having a core armature, an operating head on said armature and substantially coaxial with said perforating means, means on said head for actuating said feed wheel, and means operable by said head for actuating said perforating means.
20. In combination, a plurality of perforating means provided with collars, means for operating said perforating means, a comb for returning said perforating means to normal positions, and guide plates for said perforating means located above and below said comb.

EDWARD E. KLEINSCHMIDT.
